UNITED STATES PATENT OFFICE.

ANDREW L. LEWIS, OF PETERSBURG, VIRGINIA.

SLIDING DOOR.

No. 846,824.

Specification of Letters Patent.

Patented March 5, 1907.

Application filed March 29, 1906. Serial No. 308,799.

To all whom it may concern:

Be it known that I, ANDREW L. LEWIS, a citizen of the United States, residing at Petersburg, in the county of Dinwiddie and State of Virginia, have invented new and useful Improvements in Sliding Doors, of which the following is a specification.

This invention relates to sliding doors particularly adapted for use on cars; and the primary object of the same is to provide a device of this class with antifrictional engaging means at the upper and lower extremities and at an intermediate point to obstruct any tendency of binding of the door at any point and facilitate the opening and closing movements of the door, as well as to compensate for shrinkage, warpage, and settling of the parts of the door structure and the car side to which it is applied.

20 The invention consists in the construction and arrangement of the several parts, which will be more fully hereinafter set forth.

In the drawings, Figure 1 is a side elevation of a portion of a car side, showing the improved sliding-door organization applied thereto. Fig. 2 is a transverse vertical section through the parts shown by Fig. 1. Fig. 3 is a horizontal section on the line 3-3, Fig. 1.

30 Similar numerals of reference are employed to indicate corresponding parts in the several views.

The numeral 1 designates a car side having an opening 2 therein and provided with a 35 door-stop 3 adjacent to one side wall of the opening and a limiting-stop 4 at a suitable distance from the opposite side wall of the opening 2 to check the movement of the sliding door 5 with relation to the said opening.

40 The door 5 may be of the ordinary construction, without the outside battens, and the upper and lower ends thereof engage upper and lower tracks, sufficient play or looseness of the door, particularly in a vertical direction, being permitted to obviate jamming or binding and to compensate for shrinkage or settling of the parts of the car structure adjacent to the door. The upper track includes a metallic strip 6, which is let 45 into a longitudinal slot 7, extending over the door or opening 2 and secured by suitable fastenings. By securing the strip 6 in the longitudinal slots, as specified, any tendency toward loosening of the said strip will be 55 obviated in view of the fact that the lower edge thereof bears against the lower marginal

wall of the slot 7. Arranged parallel with and at a suitable distance outwardly from the metallic strip 6 is a second metallic sheathing-strip 8, the inner opposing sides 60 of the two strips being engaged by rollers 9, applied to opposite sides of the upper end of the door 5 through the medium of suitable carrying-plates 10, let into the front and rear sides of the upper extremity of the door, 65 so as to provide a flush fitting.

The rollers 9 have loose movement and serve as upper antifrictional means for easing the operation of the door, as well as preventing the upper extremity of the latter from 70 moving inwardly or outwardly. The lower track consists of inner and outer metallic strips 11 and 12, the inner strip 11 being secured to the car sides close to the lower terminal of the opening 2 and the outer strip 12 75 also secured to the car side by brackets 13. Between the two strips 11 and 12 a series of longitudinally-aligned rollers 14 are mounted and are located near to the lower edges of the said strips, so as to form a way sufficiently 80 deep to receive the lower ends of the door 5. The lower end of the door 5 has a metallic wear-strap 15 secured thereover to contact with the rollers 14, the latter being arranged close enough to prevent any sagging tendency 85 of the door. Between the limiting-stop 4 and the adjacent side wall of the opening 2 and nearer to the latter wall upper and lower antifrictional rollers 16 are held in the car side by carrying-plates 17, which are let into slots or 90 recesses flush with the said car side.

The inner side of the door has a pair of metallic wear-straps 18 extending thereacross fully from one side to the other and countersunk to contact with the rollers 16. These 95 wear-straps also have the additional function of strengthening the door 5 and obviating to a material extent warpage or misshaping of the door. The door 5 will also be provided with upper and lower operating-grips 19 and a suitable fastening 20.

From the foregoing description the operation of the door will be readily understood, and the advantages accruing from the disposition of the rollers, as stated, is that no part of the door can become jammed, and it may be quickly opened and closed. Furthermore, the rollers are so arranged both in the door and in connection with the car side that they will not be affected by vibration or jar instituted by movement of the car.

It will also be seen that the improved slid-

ing-door organization may be readily applied to a car side.

While the improved features have been described as being applied to one door, it will be understood that they may be equally well used with double doors and that instead of using the same with a car they might be employed in connection with barn or other doors.

10 Having thus described the invention, what is claimed is—

15 A sliding-door organization comprising a support having an upper track free of rollers and including inner and outer metallic members, a lower track having inner and outer members with longitudinally-aligned rollers held therebetween and below the upper edges thereof, upper and lower vertically-aligned rollers on the support between the upper and 20 lower tracks, and a door engaging the tracks

at its upper and lower extremities and having the weight thereof imposed on the lower rollers exclusively, the said door being provided with rollers projecting from the inner and outer surfaces of the upper end thereof, 25 the said inner rollers being adjacent to the ends of the door and an outer roller located at about the center of the same, and the intermediate portion of the inner side of the door having metallic strips extending fully 30 thereacross which are held in contact with the vertically-aligned rollers between the upper and lower tracks.

In testimony whereof I have hereunto set my hand in presence of two subscribing witnesses.

ANDREW L. LEWIS.
